UNITED STATES PATENT OFFICE.

BERTRAM J. GOLDSMITH AND EMIL KOEB, OF NEW YORK, N. Y., ASSIGNORS TO PERFECT WINDOW REGULATOR CORPORATION, OF LONG ISLAND CITY, NEW YORK, A CORPORATION OF DELAWARE.

WINDOW REGULATOR.

Application filed May 11, 1925. Serial No. 29,631.

This invention relates to devices adapted to open and close windows such for instance as those in closed automobiles in which the window is slidable into and out of a suitable 5 window well.

The principal object of the invention is the production of a window regulator of the above character which shall be simple in construction and easy of installation.

10 A further object of the invention is the production of a window regulator of the above character which shall be so constructed as to always exert an effort centrally of the window for raising or lowering the same 15 whereby the possibility of the window jamming in or against one of its guides is eliminated.

Further objects and advantages of the invention will appear from the accompanying 20 description.

In the accompanying drawings in which a practical embodiment of the invention is illustrated:

25 Fig. 1 is a front elevation of a fragmentary portion of a window showing the regulator of the invention applied thereto.

Fig. 2 is a horizontal section on the line 2-2 of Fig. 1.

30 Fig. 3 is a horizontal section on the line 3-3 of Fig. 4.

Fig. 4 is a front elevation of a part of the device.

Fig. 5 is a vertical cross-section on the line 5-5 of Fig. 4.

35 Fig. 6 is a view similar to Fig. 4 but showing the device in a different position.

Referring in detail to the several figures of the drawings:

40 The side members of a rectangular frame are indicated at 1 which frame may, if so desired, be the frame of a vehicle door. These side members are provided at their lower portions with inner and outer walls 2 and 3 respectively extending thereacross 45 and fastened thereto in any desirable manner to form a window well into which a window 4 is vertically slidable in suitable channels or guideways 5 with which said side members are provided.

50 A supporting plate is indicated at 6 and is secured to one of said side members within the window well preferably by suitable screws as shown in Fig. 1. Mounted in said plate and extending through the wall 2 is

a stud shaft 7 carrying on one end a crank 55 or handle 8. Said stud shaft also carries a pinion 9 and the end of said shaft is reduced as illustrated and extends through an elliptical slot 10 of a plate 11 and is held in engagement with said slot by a headed screw 60 12 screwed in the end of said stud shaft 7.

The plate 11 has fastened thereto by suitable rivets an operating arm 13 provided with a slot 14 receiving a headed pin 15 which is mounted or screwed to the supporting plate 6. The outer end of said operating arm is pivoted to a plate or bracket 16 which is secured in any desirable manner to the lower edge of the window. 17 indicates a rack which is screwed or otherwise fastened to the plate 11 adjacent the inner wall of its slot 10 and which follows the contour of said slot. The pinion 9 meshes with said rack 17.

To raise or lower the window into and out of the window well the crank or handle 75 8 is rotated in the proper direction and motion is transmitted therefrom through the shaft 7, pinion 9, rack 17, plate 11, arm 13 and to the window. The movement of the arm will not only be a pivotal one on the pin 15 as a pivot but will be a sliding one on said pin as well, as is obvious because of the meshing of the pinion 9 with the rack 17 and because of the configuration of said rack. This arrangement permits the arm 13 to always exert its effort against the window centrally thereof whereby an easy and smooth operation of the window is obtained.

What we claim as our invention is:—

1. In a window regulator, a pivoted arm 90 engaging the window and provided with a curved slot therein, a crank for swinging said arm on its pivot to raise or lower the window and means connecting said arm and crank and extending through said curved 95 slot.

2. In a window regulator, an arm provided with a slot therein and capable of a pivotal movement and a movement longitudinally of its axis, a crank for actuating said 100 arm to raise and lower the window and means connecting said arm and crank and extending through said slot.

3. In a window regulator, a support, a plate having a curved slot therein and mounted on said support, a shaft extending through said slot, a pinion on said shaft, a rack carried by said plate and meshing with

said pinion, an operating arm engaging the window and movable with said plate and means for rotating said shaft.

4. In a window regulator, a plate, an elliptically-shaped rack carried by said plate, a shaft, a pinion thereon meshing with said rack, an arm secured to said plate and engaging the window and means for rotating said shaft.

10 5. In a window regulator, a plate, an elliptically-shaped rack secured to said plate, a pinion meshing with said rack, means for rotating said pinion and an arm pivoted to said plate and to the window.

15 6. In a window regulator, a plate, a curved rack secured to said plate, a pinion meshing with said rack, means for rotating said pinion, a slotted arm pivoted to the window and a pin extending through the slot in said arm, 20 said arm being capable of a slidable and pivotal movement on said pin.

7. In a window regulator, a support, an arm pivotally secured to said support and to the window, a plate provided with a curved 25 slot therein and fastened to said arm, a shaft mounted on said support and extending through said slot, a pinion carried by said shaft, a rack secured to said plate adjacent said slot and meshing with said pinion and 30 a crank for rotating said shaft.

8. In a window regulator, a support, a slotted arm pivoted to the window centrally thereof, a headed pin extending through the

slot in said arm and carried by said support, a plate having a curved slot therein, said 35 plate being secured to said arm, a rack fastened to said plate adjacent said curved slot, a shaft mounted in said support, a pinion carried by said shaft and meshing with said rack and a crank on said shaft for rotating 40 the same.

9. In a window regulator, a movable device having a curved slot therein, a rack, a pinion meshing with said rack, operating means, means connecting said operating 45 means and said pinion and extending through said slot and an operating arm engaging the window and movable with said device.

10. In a window regulator, a movable elliptically-shaped rack, a toothed member meshing with said rack, a pivoted arm engaging the window and connected to said rack and means for rotating said toothed member to raise or lower the window. 55

11. In a window regulator, a pivoted arm engaging the window, an elliptically-shaped rack associated with said arm, a toothed member meshing with said rack and means for actuating said toothed member to raise 60 or lower the window.

Signed at New York, in the county of New York and State of New York, this 30th day of April A. D. 1925.

BERTRAM J. GOLDSMITH.
